UNITED STATES PATENT OFFICE.

HYMAN CHERNOFF, OF NEW YORK, N. Y.

POCKET LATCH.

Application filed January 19, 1925. Serial No. 3,469.

To all whom it may concern:

Be it known that I, HYMAN CHERNOFF, a citizen of United States, residing at New York city, in the county of New York and State of New York, have invented new and useful Improvements in Pocket Latches, of which the following is a specification.

This invention relates to improvements in pocket latches and has for its primary object, the provision of a latch composed of a pair of co-acting parts adapted to be respectively attached to opposite walls of a safety pocket in such manner as to be concealed from view.

Another object of the invention resides in a pocket latch for attachment to safety pockets used for the keeping of money and other valuables and which cannot be tampered with by unauthorized persons without detection on the part of the wearer of the garment, as the latch cannot easily be actuated by one unfamiliar with its construction and operation.

With these and other objects in view, the invention resides in certain novel construction and combination and arrangement of parts, the essential features of which are hereinafter fully described, are particularly pointed out in the appended claim, and are illustrated in the accompanying drawing, in which:—

Figure 1 is a front elevation of a safety pocket showing my improved latch in position thereon.

Figure 2 is a perspective view showing the pocket in an opened position to illustrate the relative position of the co-acting parts.

Figure 3 is an enlarged vertical sectional view on the line 3—3 of Figure 1.

Figure 4 is an enlarged vertical longitudinal sectional view through the latch per se.

Figure 5 is a horizontal sectional view through the latch.

Referring more particularly to the drawing, the reference numeral 10 designates a portion of a garment such as a coat or trousers and which is formed with a pocket 11 of the usual well-known construction and which is preferably the pocket formed in the inside of a man's coat. Arranged to the rear of the pocket 11 is a second pocket 12 which I shall term as a safety pocket, the mouth 13 of which is disposed above the mouth 14 of the pocket 11 although access to the pocket 12 is had through the mouth 14 of the pocket 11. The mouth 13 is sealed

against entrance by an unauthorized person by my improved means 15 arranged between the mouths of the respective pockets.

A flap 16 seals the mouth 13 of the pocket 12 and has secured to the inside thereof by a stitching or the like, a flat elongated plate 17 which constitutes the male member of the latching means 15. Mounted within the body of the plate for sliding movement is a latching bar 18 formed with a manipulating knob 19 at one end thereof and which projects from one end of the plate. Latching fingers 20 are formed on the bar and extend through slots in the face of the plate for co-action with a second plate 22 stitched or otherwise secured to the outer wall of the inner pocket 12. A spring 21 tends to normally hold the bar in a retracted position within a plate with the fingers 20 at one end of the slots. The plate 22 is identical in shape to the plate 17 and serves as a female member of the latching means, as the same is formed with slots of the recesses 23 for receiving the respective fingers 20 of the latching bar, said fingers engaging the ends of the slots when in a latched position.

When the pocket 12 is latched against entrance the plates 17 and 22 are in co-acting position with the fingers 20 in engagement with the end of the recesses in the plate 22 and are held in such position by the spring 21. The flap 16 conceals the said plates as will be clearly seen in Figures 1 and 3 of the drawing. When access to the pocket 12 is desired, the hand is inserted in the mouth 14 and the manipulating knob 19 is grasped and pulled against the tension of the spring 21 to disengage the fingers from the plate 22 thereby permitting the walls of the mouth 13 to be separated. The mouth 13 is easily sealed by bringing the plates into co-acting engagement with the fingers disposed within the recesses 23 and in engagement with the ends of the same.

From the foregoing description, it will be seen that I have provided a pocket latch which is entirely concealed from view and which may be conveniently operated when desired by the wearer of a garment to which the same is applied, but any attempt by one unfamiliar with its operation may be easily detected.

What is claimed as new is:—

A pocket latch comprising a pair of separable members adapted to be respectively

secured to opposite walls of a pocket, a lock bar slideable within one of said members and having one end extending beyond one end of the member and provided with a manipulating portion, spaced L-shaped fingers extending from said latch bar and movable in respective slots provided in one face of said member, the other of said members having spaced slots therein for receiving

the respective L-shaped fingers, and a spring 10 carried by said first member and acting against one of said L-shaped fingers for holding all of said fingers in co-acting engagement with the end walls of said slots provided in the second member.

In testimony whereof I have affixed my signature.

HYMAN CHERNOFF.
